HOUSING FOR A PHOTOELECTRIC CONTROL UNIT OR SIMILAR ARTICLE

Philip Garnick, Needham, Mass., assignor to Sigma In-
struments, Inc., a corporation of Massachusetts

Filed Oct. 3, 1960, Ser. No. 62,361

Term of patent 14 years

(Cl. D26—1)

Fig. 1 is a perspective view of a housing for a photoelectric control unit or similar article, showing my new design;

Fig. 2 is a side elevational view thereof;

Fig. 3 is a top plan view thereof;

Fig. 4 is a vertical sectional view on line 4—4 of Fig. 3; and

Fig. 5 is a horizontal sectional view on line 5—5 of Fig. 2.

The dominant features of my new design are shown in solid lines in the drawing.

This application is a continuation in part of my application filed June 8, 1959, Serial No. D.56,239, now abandoned.

I claim:

The ornamental design for a housing for a photoelectric control unit or similar article, as shown and described.
